UNITED STATES PATENT OFFICE.

NORVIN W. PERRIN, OF CHICAGO, ILLINOIS.

DESIGN FOR A LAMP SHADE.

Application filed January 23, 1922. Serial No. 330. Term of patent 3½ years.

To all whom it may concern:

Be it known that I, NORVIN W. PERRIN, a citizen of the United States, residing at Chicago, in the county of Cook, State of Illinois, have invented a new, original, and ornamental Design for a Lamp Shade, of which the following is a specification, reference being had to the accompanying drawing, forming a part thereof.

The figure is a perspective view, showing my new design.

I claim:

The ornamental design for a lamp shade, as shown.

NORVIN W. PERRIN.
